UNITED STATES PATENT OFFICE

103,550

DESIGN FOR A FOUR-ENGINED FLYING BOAT

Isaac M. Laddon, San Diego, Calif., assignor to
Consolidated Aircraft Corporation, a corpora-
tion of Delaware

Application September 10, 1936, Serial No. 64,794

Term of patent 7 years

To all whom it may concern:

Be it known that I, Isaac M. Laddon, a citizen
of the United States, residing at San Diego, in
the county of San Diego and State of California,
have invented a new, original, and ornamental
Design for a Four-Engined Flying Boat, of which
the following is a specification, reference being
had to the accompanying drawings, forming part
thereof:

Fig. 1 of the drawings is a plan view of an air-
plane embodying the new design;

Fig. 2 is a front elevation of the same; and
Fig. 3 is a side elevation of the subject airplane.
I claim:

The ornamental design for a four-engined fly-
ing boat substantially as shown.

ISAAC M. LADDON.
